UNITED STATES PATENT OFFICE

133,061

DESIGN FOR A LAPEL BUTTON OR SIMILAR ARTICLE

Fred Lay, Bozeman, Mont.

Application August 19, 1941, Serial No. 102,952

Term of patent 3½ years

To all whom it may concern:

Be it known that I, Fred Lay, a citizen of the United States, residing at Bozeman, in the county of Gallatin and State of Montana, have invented a new, original, and ornamental Design for a Lapel Button or Similar Article, of which the following is a specification, reference being had to the accompanying drawing, forming part thereof.

I claim:

The ornamental design for a lapel button or similar article, as shown.

FRED LAY.
